CLAIM

The ornamental design for a circular trash can with small top aperture, as shown and described.

DESCRIPTION

FIG. 1 is a front perspective view of a new design for a circular trash can with small top aperture.

FIG. 2 is a front view of the design of FIG. 1.

FIG. 3 is a rear view of the design of FIG. 1.

FIG. 4 is a left side view of the design of FIG. 1.

FIG. 5 is a right side view of the design of FIG. 1.

FIG. 6 is a top view of the design of FIG. 1.

FIG. 7 is a bottom view of the design of FIG. 1; and,

FIG. 8 is a perspective view of the design of FIG. 1.

The broken lines in the drawings illustrate portions of the circular trash can design with small top aperture that form no part of the claimed design.

The broken line shown in FIG. 8 depicts environment and forms no part of the claimed design.

1 Claim, 8 Drawing Sheets
